(57) **CLAIM**

The ornamental design for a tote bag with variable gathers and exposed strap, as shown and described.

DESCRIPTION

FIG. 1 is a front elevational view of a tote bag with variable gathers and exposed strap in a substantially uncompressed state and having a carry strap; the rear elevational view being a mirror image thereof;

FIG. 2 is a front elevational view of the tote bag with variable gathers and exposed strap in a partially compressed state, the rear elevational view being a mirror image thereof; FIG. 3 is a front elevational view of the tote bag with variable gathers and exposed strap in a substantially compressed state, the rear elevational view being a mirror image thereof;

FIG. 4 is a left side view of FIG. 1, the right side view being the mirror image thereof;

FIG. 5 is the left side view of FIG. 2; the right side view being the mirror image thereof;

FIG. 6 is the left side view of FIG. 3; the right side view being the mirror image thereof;

FIG. 7 is a bottom perspective view of FIG. 1;

FIG. 8 is a top perspective view of FIG. 1;

FIG. 9 is a left side perspective view of the tote bag with variable gathers and exposed strap as in FIG. 1, now showing an alternative arrangement in which the bag has shading indicating a first preselected fabric and the straps have shading indicating a second preselected fabric, the right side perspective view being a mirror image thereof;

FIG. 10 is a bottom perspective view of FIG. 9; and,

FIG. 11 is a bottom perspective view of the tote bag with variable gathers and exposed strap as in FIG. 1; now showing the strap not extending around the bottom of the bag.

The broken lines shown in the Figures, including the carry straps and stitching are to show environment only and are not part of the claimed design.
